UNITED STATES PATENT OFFICE.

JAMES BURKE, OF ERIE, PENNSYLVANIA, ASSIGNOR TO BURKE ELECTRIC COMPANY, A CORPORATION OF PENNSYLVANIA.

DYNAMO-ELECTRIC MACHINE.

1,185,366.

Specification of Letters Patent.

Patented May 30, 1916.

Application filed October 9, 1907. Serial No. 396,563.

To all whom it may concern:

Be it known that I, JAMES BURKE, a citizen of the United States, residing at Erie, in the county of Erie and State of Pennsylvania, have invented certain new and useful Improvements in Dynamo-Electric Machines, of which the following is a full, clear, and exact specification.

My invention relates to dynamo electric machines, and to various features of construction, the object of my invention being in general the construction of machines which will have a high degree of efficiency, be adapted to be well ventilated throughout and be simple and economical in construction.

My invention is particularly applicable to the construction of the stationary element of such machines.

One of the important features of my invention relates to the construction and arrangement of the laminæ with special reference to machines of small construction comparatively.

Prior to my invention it has been customary to build up the laminated portion of laminæ, each forming a circular disk. By my present invention, the form of the laminæ instead of being circular on the outer periphery, is of such form that by assembling the laminæ in a certain manner, the amount of radiating surface is greatly increased and also by reason of the form of the laminæ, I secure a very material saving in amount of waste material in punching the laminæ from the sheet metal as will be afterwards explained.

Another feature of my invention relates to the form of the supporting frame with a view to securing proper alinement of the rotating element which is of special importance in machines having a very small air gap, such as induction motors for example.

Another feature of my invention relates to the form of the frame with a view to securing free circulation of air, and consequently improve the ventilation of the machine.

Another feature of my invention relates to means for accurately and simply adjusting the position of the rotating element.

In machines having small air gaps, if the rotating element is properly centered when the machine is first operated, the wear of the bearings will cause the air gap at the

lower part of the machine to be decreased a comparatively large amount and that at the upper correspondingly increased. By my invention I provide suitable means whereby the rotating element may be quickly and accurately adjusted to its proper position.

These and other features of my invention will be understood from the following description and accompanying drawings, in which—

Figure 1 is a vertical sectional view of one form of machine embodying certain features of my invention; Fig. 2 is an end view thereof; Fig. 3 is a side view of the field frame partly in section and with certain parts removed; Fig. 4 is a face view of the laminæ showing their form and manner of assembling; Fig. 5 is an edge view of assembled laminæ; Fig. 6 is an explanatory diagram; Fig. 7 is a sectional view of end bracket and adjoining portions of the main frame of a machine embodying certain additional features of my invention; Fig. 8 is an end view thereof; Fig. 9 is a side view of adjusting means for the end bracket shown in Fig. 7 and Fig. 8; and Fig. 10 is an end view of the adjusting means with the bolt and nuts removed.

Figs. 1 to 3 inclusive, illustrate the construction of an induction motor, the shaft 1 of which supports a spider 2 having the outwardly extending portions 3, 4. The spider supports the laminæ 5 of the rotating element, and which are clamped between the end rings 6, which have extensions for supporting the windings 7 of the rotating element. The main frame is shown at 8, and is provided with ventilating openings 9 on its outer cylindrical surface as indicated in Fig. 3. The frame 8 extends outwardly at the ends to such an extent as to cover and shield the armature windings 10 of the stationary element, and is provided with inwardly extending side portions 11, 12. From the side portion 11 extends a series of inwardly projecting ribs 13 as shown in Fig. 3, these ribs being spaced angularly at about 45 degrees from each other and extend inwardly beyond the middle of the main frame, but do not extend the full width of the machine. From the side portion 12 extends a corresponding set of ribs 14, and which overlap the ribs 13, leaving however a considerable space between them.

The laminæ 15 are assembled upon and supported by the ribs 13, 14, and it will be seen that by reason of the ribs not extending fully across the frame, air may freely circulate from one part of the frame to another and out through openings 9. The laminæ 5 and 15 are divided in sections as shown in Fig. 1 and have any suitable form of separator between sections so as to allow the air to pass freely through the machine and out through the spaces between the ribs 13 and 14 and through the openings 9. The air currents which are formed by reason of this construction of the ribs, tend to create a continual flow of air throughout all the parts and largely avoid formation of air chambers with no circulation, and which, if not avoided cause unnecessary heating of the machine.

One form of laminæ and manner of assembling which involves an important feature of my invention is illustrated in Figs. 4, 5 and 6. It has been customary to punch the laminæ with a circular outline on the outer periphery when used in the stationary element, as indicated by the dotted lines 16, in Fig. 6. It is apparent from this figure that in cutting such a circular disk from sheet metal there is a considerable waste of material at the corners, the outline of the square plate required being indicated by the character 17. In accordance with my invention the laminæ are not cut in the circular form, and I thereby considerably reduce the amount of waste metal. My preferred form is indicated in full lines in Fig. 6, and the laminæ are given some octagonal form having the four opposite sides 18 and the four rounded corners 19. The rounded parts 19 are on the arc of the same circle and are adapted to fit within the ribs 13, 14 of the main frame. The key-way 20 in the laminæ is made at about the junction of one of the straight parts 18 and a curved part 19. In the bottom of the main frame is formed a rib 21, somewhat heavier than the others and which is provided with a key-way adapted to receive the key 22, which also engages the key-way 20 of the laminæ and so prevent any angular displacement of the laminæ. When the laminæ are assembled certain of them are reversed so that a rounded part of one lamina is adjacent to the straight part of an adjoining lamina, although the teeth and key-way always coincide. This arrangement will be understood from Figs. 4 and 5, the front lamina in Fig. 4 being shown in a heavy full line, and the lamina in the rear which are reversed being indicated by a light line which is partly dotted. If desired, alternate laminæ may be reversed or several adjoining laminæ may be assembled in the same manner and then a corresponding number of adjoining laminæ reversed and so on, but the final result is that the outer surface of the laminæ is of circular form having a slotted outer periphery. Moreover, there is no substantial difference in the amount of metal at any cross section taken through the laminæ. The deeply recessed outer periphery of the laminæ produces a very much increased radiating surface which greatly assists in keeping the motor at a low temperature. Not only is the radiating surface greatly increased by this form of construction, but the uniformity of the path of the magnetic flux is preserved, and moreover an important saving of the sheet iron is attained. It will also be seen that only one form of die is necessary for punching all of the laminæ. The laminæ will, of course, preferably be provided with teeth adapted to receive the windings 10. The ribs 13 are shown provided with shoulders 23 which retain the end plate on one side of the assembled laminæ in position, and for retaining the opposite end plate, any suitable form of key may be inserted into key-ways 24 of the ribs 14.

The construction of the end brackets and the location of the bearings for the shaft 1 are such as to avoid, as far as possible, improper centering of the shaft. The end brackets are of similar construction and comprise a bearing 25 of suitable form, from which extend the arms 26 to the outer rims 27. The circular rims 27 seat in corresponding recesses in the side portions 11, 12 of the main frame. The end brackets are fixed in position in any suitable manner, as by the bolts 28 which pass through the rims 27 and engage the side portions of the main frame. It will be seen from an inspection of Fig. 1, that the bearing in each end bracket closely approaches the spider 2 of the rotating element coming somewhat within the extensions 3 and 4 thereof, and within the end connections of the conductors on the rotating element. Also the main frame 8 extends beyond the end connections of the stator windings, and the end bracket instead of being curved and arching outwardly, is located throughout in one plane substantially. This construction results in the middle of the bearing being located substantially in the plane of union between the end bracket and the side portion of the main frame. This construction is particularly designed to overcome inaccuracy in alinement of the bearings and shaft when assembling or reassembling the parts. If we assume that the parts are originally properly centered and turned, it is very likely to occur that in reassembling, the engaging surfaces will not be clean and foreign material may oftentimes be located between the engaging faces when bolting the end brackets in place. Suppose for example, that in assembling an end bracket, some material prevented the face of

the rim 27 from engaging the face of the side portion 12 at the top of the frame and that the parts were separated at that point by a certain fraction of an inch, whereas, at 5 the bottom of the frame the engagement of the end bracket was a proper one. This would result of course in the top portion of the end bracket being located outwardly some distance on an arc of a circle of which 10 the bottom of the end frame would be the center. With my form of construction, however, the displacement of the bearing from its proper position or from alinement would not be material, owing to the fact 15 that the middle of the bearing is in the plane substantially with the face of the end bracket, the result being merely slight axial displacement of the bearing. On the other hand, if the bearing were located at a considerable distance to one side of the plane 20 of the face of the end bracket, the bearing would not only be displaced somewhat axially, but being to one side of the plane of engagement between the end bracket and the main frame, it would be displaced on the arc 25 of a circle having the bottom of the end bracket as a center and would consequently be displaced materially below the proper position of alinement, and thus cause a material difference in the alinement of the bearing and an improper change in the air 30 gap. Similarly, it will be seen that the location of some foreign material at any other point between the face of the end bracket 35 and the main frame would cause a material displacement in the former types of construction.

In large machines, where the weight of the rotating element is comparatively great 40 and the tension considerable, the wear of the bearings which takes place causes the air gap below the rotating element to become diminished appreciably in the course of time and the air gap above the rotating element 45 to be correspondingly increased. In machines where this is likely to occur, it is desirable to provide some convenient means of adjustment so as to easily and quickly center the rotating element. I accomplish this result by means of the construction illustrated 50 in Figs. 7 to 10, inclusive. In Figs. 7 and 8, are indicated a side portion 29 of a main stationary frame 30, and an end bracket having a bearing 31 for journaling the shaft 32, 55 the arms of the end bracket being shown at 33 and the outer rim at 34 which seats in a recess formed in the side portion 29.

It will be understood that the construction of the remaining parts of the stationary and rotating elements may be such as shown in Figs. 1 to 5, and are omitted in Figs. 7 and 8 as they have already been described. The end bracket when adjusted to proper position is clamped in place by the 60 bolts 35 which pass freely through holes in

the end bracket and engage the side portion of the main frame. Upon the main frame at the bottom is formed a seat 36 upon the face of which are placed adjusting wedges 38, 39, the former being connected to the support 36 by any suitable means such as dowel pins. The wedges 38, 39 have their engaging faces inclined as shown in Fig. 9, the wedge 38 having a lug 40 through which the threaded bolt 41 of the wedge 39 freely 75 passes. The position of wedge 39 is adjusted by turning the nut 42 against the lug 40, the nut 43 serving as a lock nut. The upper face of the wedge 39 engages the lower face of a lug 44 formed on the end 80 bracket. Movement of wedge 39 will therefore serve to adjust the end bracket to any desired position. Further adjusting means for the end brackets and for fixing the same in any desired position are provided by two 85 lugs 45 on opposite sides of the shaft, and which are on the inner face of the end bracket as indicated by dotted lines in Fig. 8. A similar lug is formed at the upper part of the end bracket as shown at 46. 90 Through these lugs extend adjusting bolts 47, the ends of which are adapted to engage the inner periphery of the side portion 29 of the main frame. It will be seen that by means of the bolts 47 in lugs 45, the end 95 brackets may be adjusted sidewise in any desired position, and secured in such position by screwing the bolts 35 up tightly against the main frame. Thus, by means of the adjusting wedges at the bottom of the 100 end bracket, and further, by means of the adjusting bolts 47 in the lugs 45 and 46, means are provided which serve to accurately and securely adjust the end bracket to any desired position, the bolts 35 serving to retain the end bracket in position 105 after adjustment. Consequently, in assembling the machine, or when a new adjustment of the position of the rotating element is desired, the desired position and adjustment may be quickly and accurately accomplished by means of my invention. Although one end bracket is shown in Figs. 7 and 8, it will be understood that a similar end bracket will be provided at the opposite 110 end of the main frame.

Although I have illustrated and described specifically certain forms of my invention, it will be understood that my invention or certain features thereof, may be embodied in 115 other desirable forms of construction without departing from the scope of my invention.

Having thus described my invention, I declare that what I claim as new and desire to 120 secure by Letters Patent, is,—

1. In a dynamo electric machine, the combination of a stationary frame, laminæ supported within said frame and in fixed relation to said frame, each of said laminæ ex- 130

- tending a complete circumference but having a periphery formed of straight and curved portions, the straight portions of certain of said laminae being displaced relative to the straight portions of certain other of said laminae, thereby forming a core of substantially uniform magnetic reluctance.
2. In a dynamo electric machine, the combination of a stationary frame, laminæ supported within said frame and in fixed relation to said frame, each of said laminae extending a complete circumference but having a periphery formed of alternate straight and curved portions, the straight portions of certain of said laminae being displaced relative to the straight portions of certain other of said laminae, thereby forming a core of substantially uniform magnetic reluctance.
3. In a dynamo electric machine, the combination of a stationary frame, and laminæ supported thereby, each lamina extending a complete circumference and having an outer periphery partly curved and partly straight, certain of the laminae being alternately arranged so that a curved part of one lamina adjoins the straight part of the next lamina.
4. In a dynamo electric machine, the combination of an outer stationary frame, and laminæ within and supported by said frame, each of said laminae extending a complete circumference, said laminae forming a core, the outer periphery of which is circumferentially recessed, substantially as described.
5. In a dynamo electric machine, the combination of an outer stationary frame, and laminae within and supported by said frame, each of said laminae extending a complete circumference, said laminae forming a core the outer periphery of which is circumferentially recessed and all of the laminae being of similar outline.
6. In a dynamo electric machine, the combination of an outer stationary frame, laminae supported within said frame, each of said laminae extending a complete circumference, a key between said frame and laminae, said laminae forming a core the outer periphery of which is recessed circumferentially and all of the laminae being of similar outline.
7. In a dynamo electric machine, a stationary frame, laminae supported within said frame, each of said laminae having a complete set of teeth on its inner periphery and the outer periphery being other than circular, the laminae being staggered with reference to each other so as to form exterior circumferential recesses.
8. In a dynamo electric machine, a stationary supporting frame having inwardly extending ribs which are in staggered relation to each other and extend only partly across the frame, and laminae supported by said ribs, substantially as described.
9. In a dynamo electric machine, the combination of a frame having supporting ribs arranged in series and which extend only part of the width of said frame, one or more ribs of one series overlapping one or more ribs of another series, and laminae supported by said ribs.
10. In a dynamo electric machine, the combination of a stationary frame having exterior ventilating openings, the same frame having ribs arranged in a plurality of series extending inwardly but which extend only part of the width of said frame, one or more ribs of one series overlapping one or more ribs of another series forming interconnected airspaces, and laminae supported by said ribs, substantially as described.
11. In a dynamo electric machine, the combination of a stationary frame, a rotating element, an end bracket for supporting the said rotating element, and means adjustable on the inside of said end bracket for adjusting the position of said end bracket relatively to said frame.
12. The combination of a stationary element, a rotating element, an end bracket for supporting the shaft of said rotating element, and wedging means interposed between said end bracket and said stationary element for adjusting the position of said end bracket with reference to said stationary element in a vertical direction, said wedging means having a surface slidably movable relatively to said end bracket.
13. In a dynamo electric machine, the combination of a rotating element, a stationary element, an end bearing bracket, the middle of the bearing and the supporting portion of said bracket being located substantially in the plane of engagement between the bearing bracket and the main frame, and means adjustable on the inside of said end bracket for adjusting the position of said end bracket relatively to said frame.
14. In a dynamo electric machine, the combination of a rotating element, a stationary element having outwardly extending windings, the main frame of said stationary element extending outwardly to cover and shield said windings, an end bearing bracket having the middle of the bearing and the supporting portion of said bracket located substantially in the plane of engagement between the end bracket and the main frame, and a plurality of adjusting devices adjustable on the inside of said bearing bracket for adjusting the position of said bearing bracket relatively to the main frame.
15. In a dynamo electric machine, the combination of a frame having ventilating

openings, said frame having ribs extending inwardly but a part of the width thereof, which ribs overlap each other to form interconnected air spaces, and laminæ supported by said ribs and arranged to form a core portion having circumferential recesses, substantially as described.

16. In a dynamo electric machine, a frame, an end head secured thereto, a shaft mounted in said end head, and adjustable means carried by said end head and adjustable on the inside thereof for shifting the position of said end head relatively to said frame.

15 17. In a dynamo electric machine, a frame, an end head secured thereto, a shaft mounted in said end head, and adjustable means carried by said end head for shifting the position of said end head relatively

to said frame, said adjustable means comprising a screw-threaded element adjustable on the inside of said end head. 20

18. In a dynamo electric machine, a frame, a vertically extending end head secured thereto, a horizontally extending 25 shaft, mounted in said end head, and adjustable means for shifting the relative position of said frame and said end head perpendicular to the axis of said shaft, said means comprising a screw-threaded element 30 on the inside face of said end head.

In testimony whereof I affix my signature, in presence of two witnesses.

JAMES BURKE.
